ATTORNEY.

UNITED STATES PATENT OFFICE.

ELVIN B. DUNGAN AND JAMES G. RAMSDELL, OF PHILADELPHIA, PENNSYLVANIA.

DESIGN FOR A PIANO-STOOL.

SPECIFICATION forming part of Design No. 19,325, dated October 1, 1889.

Application filed August 21, 1889. Serial No. 321,530. Term of patent 3½ years.

To all whom it may concern:

Be it known that we, ELVIN B. DUNGAN and JAMES G. RAMSDELL, citizens of the United States, residing in the city and county of Philadelphia, State of Pennsylvania, have invented and produced a new and original Design for Piano-Stools, of which the following is a specification, reference being had to the accompanying drawings, forming part thereof. The essential feature of our design for a piano-stool is the seat and standard thereof, simulating a toadstool or mushroom. In the drawings, A designates the seat of a piano-stool, and B designates the standards thereof, said seat and standards being re-

spectively of the form of the head and stem of a toadstool or mushroom.

C designates the base of the stool, the same being of the form of a plot of earth, the standard B rising therefrom.

We claim—

A design for a piano-stool, consisting of a seat and standard simulating a toadstool and a base, substantially as shown and described.

ELVIN B. DUNGAN.
JAMES G. RAMSDELL.
